GARMENT PROTECTING HANGER

Solomon Axelrod, Bronx, N. Y.

Application November 1, 1944, Serial No. 561,404

3 Claims. (Cl. 206—7)

This invention relates to garment bags.

Broadly, it is an object of my invention to provide a garment bag in which clothes may be hung so that such clothes will be protected from dust.

More particularly, it is an object of my invention to provide a garment bag which is adaptable for use both in the home and in vehicles, such as automobiles, to protect garments hanging therein; also in offices and factories.

A further object of my invention is to provide a garment bag which can be inexpensively produced and simply folded and secured to protect garments hanging therein.

In this era, automobile travel is very extensive and a great many people prefer to hang their clothes in the automobile instead of packing such clothes tightly in luggage. I have, therefore, provided a simple garment bag which is peculiarly adapted for hanging in automobiles in order to protect clothes during travel.

For a fuller understanding of the nature and objects of my invention, reference is had to the following detailed description in connection with the accompanying drawing in which:

Fig. 1 is a plan view of my garment bag in open position.

Fig. 2 is a front view of same in closed position.

Fig. 3 is a portion of the edge of the bag showing one of the fastening means, to wit, a loop and button.

Fig. 4 is an elevation of a modification of the hook and eye portion which receives the hangers.

Fig. 5 is the opposite view of Fig. 2.

Referring to the drawing, numeral 10 represents the body portion of the garment bag comprising wing portions 11 and 12, which are divided from the central portion 13 by fold lines 14 and 15. Wing portions 11 and 12 have extending portions 16 and 17, respectively; the ends 18 and 19 of the extensions 16 and 17 being folded over and stitched to form pockets to receive weights 20 and 21. Such weights may be of wood, metal, weighted tape or like materials or in place of weights the ends may have fastening means such as buttons or snaps to join such extensions to the central portion 13.

The upper end 22 of the central portion 13 may be folded over and formed into a pocket to receive a slat 23 which may be of wood, metal or like material. A bent wire 24 is passed through an opening in slat 23 and bent into an upper eye 25 and lower eye 26; a bent wire hanger 27 is passed through the upper eye 25 in order to hang the garment bag upon a rod, hook or similar object. It should be noted that the hook may be folded

downward so that if the garment bag is to be folded and packed away, the hook 27 need not extend beyond the upper edge of the central portion 13. The usual type of garment hanger 28 may be passed through the lower eye 26 by its hook. The lower eye 26 may be large enough to pass several hooks containing several hangers therethrough. A window 29 may be placed either in the central portion 13 as shown or in either of the wing portions 11 or 12 so that an identification card may be placed therein to designate either the type of clothes within the garment bag or the name of the person to whom such clothes belong, or any other designation that may be desired.

Wing portion 11 has a vertical series of buttons 30 to cooperate with buttonholes 31 in wing portion 12; instead of buttons and buttonholes, any other well known means of fastening may be used, such as snaps or loops and buttons, separable fasteners or the like. My garment bag may be made of fabric, heavy paper, flexible plastic such as cellophane and other like materials.

In order to use my garment bag, the clothes are first placed on hangers 28, the wing portion 11 is then folded at fold line 14 upon the central portion 13, with the extending portion 16 dropping over the left side of the upper portion of the central portion so that the weight 20 falls below the upper level and helps to maintain the wing portion 11 in position over the central portion 13. The wing portion 12 is then folded at fold line 15 over the wing portion 11 with the extension 17 dropping over the right side of upper portion of central portion 13, the weighted portion 21 maintaining the wing portion 12 in position. The buttons 30 are then passed through buttonholes 31 in order to close the garment bag.

In Fig. 4 a modified bent wire hook 32 made of one piece is passed through an opening in the slat 23, the hook 32 terminating in an eye 33.

It is obvious that various modifications and changes may be made in the details of construction and materials used in my garment bag without departing from the general spirit of the invention.

I claim:

1. A garment bag of the character described, comprising a central portion and two opposed wing portions, said wing portions having extensions at their upper ends, the upper ends of said extensions having weights, the upper end of said central portion having a slat, a bent wire passing through said slat at the central portion thereof, said wire terminating in an upper eye and a lower

eye, a hook for said upper eye, cooperating fastening means upon said wing portions whereby when said wing portions are folded over said central portion and fastened together, a complete garment cover results.

2. A garment bag of the character described, comprising a central portion and two opposed wing portions divided from said central portion by fold lines, a pocket at the top of said central portion, a slat in said pocket, a hook passing 10 through the center of said slat terminating in an

eye to receive garment hangers, each of said wing portions having extensions at the upper outside ends approximately one-half the width of said wing portions, said extensions having weights at their upper ends, a window in one of said portions for receiving an identification card, and cooperating fastening means upon said wing portions for holding said portions together as a complete garment cover.
